UNITED STATES PATENT OFFICE

MAX SADINOFF, OF BROOKLYN, NEW YORK

DESIGN FOR LACE TRIMMING OR THE LIKE

Application filed May 28, 1930. Serial No. 35,795. Term of patent 3½ years.

To all whom it may concern:

Be it known that I, MAX SADINOFF, a citizen of the United States, residing in Brooklyn, county of Kings, State of New York, whose post-office address is 16 West 22nd Street, New York, county of New York, and State of New York, have invented a new, original, and ornamental Design for Lace Trimming or the like, of which the following is a specification, reference being had to the accompanying drawing, forming part thereof.

The figure is a plan view of a lace trimming showing my new design.

A single unit of my design is substantially comprised within the area defined by the indicating lines shown on the drawing.

I claim:

The ornamental design for lace trimming or the like substantially as shown and described.

MAX SADINOFF.
